UNITED STATES PATENT OFFICE.

WILLIAM FRANKENBERGER, OF LOUISVILLE, KENTUCKY, AND HALLOCK N. GILLETTE,
OF PITTSBURGH, PENNSYLVANIA, ASSIGNS TO STANDARD SANITARY MANUFAC-
TURING COMPANY, OF PITTSBURGH, PENNSYLVANIA, A CORPORATION OF NEW
JERSEY.

WASTE-VALVE.

1,254,897.

Specification of Letters Patent. Patented Jan. 29, 1918.

Application filed August 24, 1917. Serial No. 187,973.

To all whom it may concern:

Be it known that we, WILLIAM FRANKENBERGER, residing at Louisville, in the county of Jefferson and State of Kentucky, and HALLOCK N. GILLETTE, residing at Pittsburgh, in the county of Allegheny and State of Pennsylvania, both citizens of the United States, have invented or discovered certain new and useful Improvements in Waste-
10 Valves, of which improvements the following is a specification.

Our invention relates to waste valves used in connection with lavatories, bath tubs, etc., and wherein a vertically movable stopper is raised to, and held in, open position by means of a rotatable or rocking member. Its object is to provide a waste valve which is simple and inexpensive in construction and in which the movement of the finger to 20 permit the stopper to fall to closed position will be sufficiently resisted to prevent unintentional movement.

In the accompanying sheet of drawings, which form part of our specification, we 25 have illustrated the preferred embodiment of our invention. Figure 1 is a vertical sectional view of a portion of a lavatory and waste valve and operating mechanism attached thereto, and Fig. 2 a sectional view 30 taken on the line II—II, Fig. 1.

While our invention is applicable to various types of receptacles, it is shown herein in its adaptability to a lavatory bowl 1 of well known construction.

35 In the illustrative embodiment of our invention the waste opening at the bottom of the bowl is provided with a vertically disposed valve casing 2, having a valve seat 3 at its upper end. Vertically movable in such casing is a stopper having a head 4 adapted to rest upon the seat 3 to prevent flow from the bottom of the bowl through the valve casing. The lower end of the stopper is provided 40 with a tapered, preferably a conical, face 5, the purpose of which will presently be explained.

For raising the stopper to, and holding it in, open position, a finger 6 is secured to the end of a shaft 7 rotatably mounted in the 50 side of the casing 2. As indicated in the drawings, the shaft 7 is, for simplicity of construction, rotatable on an axis substantially perpendicular to that of the stopper and lying in a plane common with the stop-

per axis. Means are provided, preferably in 55 the form of lugs 8 and 9 formed integrally with the interior of the casing 2, for limiting the alternate movements of the finger.

When holding the stopper in raised position, the finger 6 is in the position indicated 60 in Fig. 2, the outer end of the finger being provided with a tapered face, which, in the position indicated, substantially registers with the conical lower end of the stopper. It will thus be seen that the line of thrust of 65 the stopper upon the finger is at the side of the axis of rotation of the shaft 7, so that the stopper may not, by pressure thereon, be moved downwardly as long as the finger is in such position. To effect a lowering of 70 the finger to permit the stopper to fall to closed position, the stopper is preliminarily raised, and in addition to this resistance to the lowering of the finger, there is a further resistance to such movement arising from the 75 extended frictional contact of the tapered face of the finger with the conical face of the stopper.

As is usual in valves of the type contemplated herein, a vertically movable rod 9 is 80 provided to rotate or rock the shaft 7 for the purpose of raising and lowering the finger 6. Preferably the outer end of the shaft is of angular cross-section for the attachment of an arm 10, which, through a link 11, 85 is connected to the rod 9. By attaching the arm 10 to one side or the other of the shaft 7, the rod 9 may be either raised or lowered to effect the lifting of the stopper. As shown herein, the arm is so attached that 90 the pulling or raising of the rod effects an opening of the valve, that is to say, a raising of the stopper. By constructing the finger and stopper, and arranging them in the manner described, the weight of the vertically 95 disposed rod 9 and link 11 will not in itself be effective to turn the shaft 7 to lower the finger 6, and thus unintentionally close the waste valve.

According to the provisions of the patent 100 statute, we have described the principle and operation of our invention together with the construction which we now consider to represent the best embodiment thereof. However, we desire to have it understood that 105 our invention may be practised by other forms of construction than that specifically shown and described.

We claim as our invention:

1. In a waste valve, the combination of a casing, a stopper vertically movable therein and having a tapered face at its lower end, a lifting finger beneath the stopper rotatable upon an axis substantially perpendicular to and lying substantially in the same plane as that of the stopper, and means for limiting the alternate movement of the finger, the line of thrust of the stopper upon the finger when the stopper is in elevated position being at one side of the axis of rotation of the finger, whereby the lowering of the finger to permit the stopper to fall will effect a preliminary raising of the stopper.
2. In a waste valve, the combination of a casing, a stopper vertically movable therein

and having a conical face at its lower end, and a lifting finger beneath the stopper rotatable upon an axis substantially perpendicular to and lying substantially in the same plane as that of the stopper, said finger having a tapered face at its upper end adapted to substantially register with the conical face of the stopper when the stopper is held in elevated position by the finger. 20

In testimony whereof we have hereunto set our hands.

WILLIAM FRANKENBERGER.
HALLOCK N. GILLETTE.
